UNITED STATES PATENT OFFICE.

FRED A. RUMNEY, OF SOMERVILLE, MASSACHUSETTS, ASSIGNOR TO UNITED SHOE MACHINERY COMPANY, OF PATERSON, NEW JERSEY, A CORPORATION OF NEW JERSEY.

EYELETING-MACHINE.

1,122,310.

Specification of Letters Patent. Patented Dec. 29, 1914.

Application filed October 6, 1909. Serial No. 521,346.

To all whom it may concern:

Be it known that I, FRED A. RUMNEY, a citizen of the United States, residing at Somerville, in the county of Middlesex and State of Massachusetts, have invented certain Improvements in Eyeletting-Machines, of which the following description, in connection with the accompanying drawings, is a specification, like reference characters on the drawings indicating like parts in the several figures.

This invention relates to improvements in eyeletting machines, and more particularly to improvements in eyeletting machines of the type disclosed in Letters Patent of the United States, No. 934,066, dated September 14, 1909, granted upon the application of George Goddu, although certain features of the invention are also applicable to machines of other types or machines for setting other forms of fasteners, such, for instance as studs or rivets.

An object of the present invention is to provide a simple and effective arrangement for retracting the punches and setting dies or sets of an eyeletting machine of the type disclosed in the patent above identified. In that machine each of the punches and sets is connected with a retracting lever which is actuated by a spring pressed plunger for retracting its respective punch or set and maintaining it out of engagement with the work. The compression springs for actuating each of the plungers are incased in a portion of the feed frame and are thus hidden from inspection. It has been found that these compression springs are liable to break or become slow in action from other causes and that on account of their concealed position the operator neglects to replace them until their complete failure results in a catastrophe to the machine. The present invention, however, contemplates a novel construction and arrangement of parts which obviates the difficulties above discussed, and at the same time simplifies the general organization of the machine and thereby reduces its cost.

To this end, an important feature of the invention consists in providing single devices for retracting both punches and both sets and in so locating such devices that they may be, at all times, readily accessible and open to inspection. Preferably the punch

and set actuating levers may be provided with rearwardly extending projections and connected in pairs by single tension springs which serve to retract simultaneously the respective pair of punches or sets.

Another object of the invention is to provide an eyeletting machine with treadle operated mechanism for varying the spread of the eyelets in order that the lowest pair of eyelets may be set at a greater distance from the edges of the lacing slit than the remaining eyelets. Heretofore it has been customary to shift the edge gages, presser feet, and guide plate, in machines of the type disclosed in the patent above referred to, by means of a hand lever which the operator was obliged to manipulate for each boot or shoe eyeleted. The present invention, however, contemplates a novel arrangement of parts whereby the shifting of the gages and guide plate may be effected from the heel end of the starting treadle while the operator employs both hands in picking up and presenting the work to the machine.

An important feature of the invention, accordingly consists in providing a flexible connection between the guide plate, upon which the presser-feet and other work-engaging members are mounted, and a treadle rod and in so guiding the flexible connecting member that the edge gages may be shifted with respect to the setting devices by depressing the treadle rod.

Another object of the invention is to provide an eyeletting machine having a relatively movable anvil plate and work rest, with means for preventing loose portions of a shoe, such as the tongue, lining, or the like, from becoming caught between said relatively movable members when one is moved toward the other. To this end the invention contemplates an arrangement of the anvil plate and work rest such that the acting surfaces of both are rendered substantially continuous, thereby preventing the occurrence of a space between them into which a part of the work could enter and become caught. As herein shown this is accomplished by mounting on one of said members a guard plate which is arranged to slide freely in a slot formed in the other member. Preferably the guard plate may be mounted on the anvil plate by means of a long reduced shank and in this construc-

tion the upsetting dies and cutting block may be retained in the anvil by having the shank passed through them.

Setting devices or sets have been usually 5 constructed of one piece of stock shaped to set the desired eyelets and uniformly tempered throughout. The present invention, however, contemplates the provision of a setting device having a short detachable and 10 replaceable portion in which the die proper is formed, the die portion being shaped to fit like a cap over the end of the body portion of the setting device. This construction is advantageous in that the die itself 15 may be formed of hardened steel while the remaining portion of the setting device may be left softer and consequently less brittle. The setting device may also be renewed at much less expense than formerly by merely 20 replacing the portion in which the die is formed.

The features and advantages above set forth and others incident to the invention will be best understood and appreciated in 25 connection with the following description taken in connection with the accompanying drawings in which,

Figure 1 is a view in elevation of the 30 punching, setting and work guiding portions of an eyeletting machine embodying the present invention; Fig. 2 is a plan view of the guide plate and anvil plate.

The machine shown in the drawings, like 35 the machine of said patent, is organized and arranged to punch two holes in the opposite sides of the upper of a shoe and then to set two eyelets in those holes and to feed the work.

The principal features of the present 40 invention, as already pointed out, reside in certain improvements in the various parts of this machine. Before proceeding to a detailed description of these parts it will be convenient to refer to the general mode of 45 operation and relative arrangement of the machine.

The machine shown in the drawings has 50 a base 2 to which is attached the frame 4 carrying the driven or operating parts and the work guiding mechanism. As in the 55 patent, this machine comprises oppositely disposed punches P and oppositely disposed sets S arranged for reciprocation in bearings in a support or feed frame 6, with the 60 anvil or die plate 8 also mounted in said support or feed frame, arranged between the oppositely disposed punches and eyelet setting dies. The feed frame and the devices carried thereby extend at an angle 65 of 45° to the vertical. The clamping members or presser feet 10 are arranged to engage the work on the opposite sides of the guide plate 12, smoothing and guiding it to the setting dies.

65 In presenting the work to the machine

the presser feet 10 yield away from the guide plate 8 allowing the opposite quarters of a shoe to be drawn over the opposite sides of the guide plate 12 with their edges against the edge guide 14 mounted on said guide plate. The machine is then set in operation whereupon the punches first advance and punch two holes in opposite sides of the upper in alignment with each other, then the feed frame 6 rises to bring the sets into 75 the position previously occupied by the punches and eyelets are presented to the sets S which insert and clinch such eyelets in the holes in the work. After the sets have clinched the eyelets in the work they 80 are released slightly but still held in engagement with the eyelets, and then the feed frame 6 is moved laterally to feed the materials the desired distance between two successive eyelet holes, the feed frame then 85 makes its return or back feed movement bringing the punches back to their original positions and the operations are repeated.

In the accompanying drawings the actuating cams and mechanism for raising and 90 swinging the feed frame 6 and the cams for actuating the set and punch operating levers 16 are omitted since they form no part of the present invention but are similar to the corresponding parts shown in Patent No. 934,066 to which reference may be had.

The operating levers 16 are actuated by cams to impart the working pressure to the punches P or to the setting dies S according as one or the other of these devices are brought into operative position by the feed frame 6. The punches P are each provided with a forked projection 18 which engages the outer end of a lever 20 pivoted on the 105 frame 6 by the pin 22. Each of the levers 20 is provided with a rearwardly extending arm 24 and extending between the arms 24 and having a swiveled connection therewith is a tension spring 26 which tends always to 110 raise the levers 20 for retracting the punches.

The setting dies S are each provided with a recessed projection or block 28 adapted to receive the end of a lever 30 also pivoted on 115 the pin 22. Each of the levers 30 is provided with a rearwardly extending arm 34 between which extends the tension spring 36 tending always to raise the levers 30 and maintain the setting dies in their retracted 120 positions. Outward movement of the levers is limited by projecting stops 31 on the levers which engage fixed abutments on the frame 6. The arms 24 of the levers 20 extend upwardly and rearwardly to clear the arms 34 of the levers 30 and are so disposed as to allow the springs 36 and 26 to extend in a parallel relation along one side of the feed frame 6 where their condition may be readily observed by the oper- 125 130

ator and the springs easily renewed if not operating satisfactorily.

The guide plate 12 is slidingly mounted upon a fixed part of the frame and carries 5 the edge guides or gages 14. Presser feet 10 are yieldingly mounted on both sides of the guide plate 12 by means of flat springs 38 and yieldingly clamp the work against the guide plate throughout the entire operation of the machine. The guide plate is 10 provided with a rearwardly extending shank 40 upon which a rack is formed to mesh with the pinion 42. It will be apparent that the spread of eyelets set in the work will depend 15 upon the position of the edge of the work with relation to the setting devices, the spread increasing as the work is moved rearwardly. In order that the operator may conveniently move the gages rearwardly 20 prior to the introduction of each new piece of work for setting the lowermost eyelets with a wider spread than the other eyelets, the guide plate 12 is provided with an eye 25 44 to which is connected one end of a flexible member such as a chain 45. The chain is guided over a guide-pulley 46 on the frame 4 and is attached to the upper end of a treadle rod 48 extending preferably to the heel end of the starting treadle (not 30 shown) by which the guide plate 12, presser feet 10 and edge gages 14 may be shifted rearwardly. The guide plate 12 with the work clamped to it is moved forwardly to its normal position and limited in its motion 35 by the pinion 42, which constitutes part of an automatic device for moving the guide plate forwardly, after the first or lowermost pair of eyelets have been set, said automatic mechanism being fully described in Patent 40 No. 934,066 above mentioned.

The anvil plate 8 carries the cutting block 50 and the upsetting dies 52 coöperating respectively with the punches P and the sets S. In order to prevent loose portions of 45 the work from getting caught between the work rest 13, which extends laterally from the guide plate, and the lower end of the anvil plate 8, a guard plate 54 is mounted on the anvil plate and arranged to slide 50 freely in a slot formed in the work rest 13. Preferably the shank 55 of the guard plate 54 may be utilized to retain the cutting block 50 and the upsetting dies 52 within the anvil plate 8 by being extended through a trans- 55 verse bore formed in these members. As shown in Fig. 2 the upper end of the shank is notched and the guard plate held in position by a locking screw set in the anvil plate. When the guide plate 12 is shifted rear- 60 wardly by the treadle through the chain 45 the work rest 13 slides upon the guard plate 54 to a position nearer the anvil plate 8 than normally but is moved back to its normal position at the end of the first cycle of the 65 machine by the pinion 42. The operation of

the anvil plate is, of course, unaffected by the shifting of the guide plate. During the feeding operation the guard plate slides toward the left between the sides of the work rest 13.

Having described my invention, what I claim as new and desire to secure by Letters Patent of the United States is:—

1. A machine for setting fasteners in sheet material, having, in combination, a 70 pair of oppositely disposed tools for punching the work, a pair of oppositely disposed tools for setting fasteners therein, means for actuating the tools of one pair, and a single device for retracting both of said last-named 75 tools. 80

2. A machine for setting eyelets or the like, having, in combination, oppositely disposed setting dies, intermediate upsetting dies, means for actuating said setting dies 85 for clenching eyelets or the like, and a single device for retracting both setting dies. 90

3. A machine for setting fasteners in sheet material, having, in combination, a pair of oppositely disposed tools for punching the work, a pair of oppositely disposed tools for setting fasteners therein, means for actuating the tools of one pair, a lever connected to each tool of said pair, and a single device 95 for operating both levers to retract both tools. 100

4. A machine for setting eyelets or the like, having, in combination, oppositely disposed setting dies, intermediate upsetting dies, means for actuating said setting dies 100 for simultaneously clenching two eyelets or the like, a lever connected with each of said setting dies, and a single device for operating both levers to retract both setting dies. 110

5. A machine for setting eyelets or the like, having, in combination, a pair of oppositely disposed punches, a pair of oppositely disposed setting dies, means for actuating said punches and dies for punching the work and setting eyelets, a single device 115 for retracting both of the punches and a single device for retracting both of the setting dies. 120

6. A machine for setting fasteners in sheet material, having, in combination, a pair of oppositely disposed tools for punching the work, a pair of oppositely disposed fastener setting tools, means for actuating all of said tools, and a single spring for retracting the oppositely disposed tools of one pair. 125

7. A machine for setting eyelets or the like, having, in combination, a pair of oppositely disposed setting dies, intermediate upsetting dies, means for actuating said setting dies for clenching eyelets or the like, and a single tension spring for retracting both setting dies and maintaining them out of engagement with the work. 130

8. A machine for setting eyelets or the like, having, in combination, an anvil plate,

4
a cutting block and upsetting dies carried thereby, a pair of oppositely disposed punches, a pair of oppositely disposed setting dies, a single device for actuating either 5 the punches or the dies, a single spring for retracting both punches and a second spring extending parallel to the first mentioned spring for retracting both setting dies.

9. A machine for setting eyelets or the 10 like, having in combination, tools for operating on the work, a coöperating anvil plate, a normally stationary work support toward and from one side of which the anvil plate is periodically moved, and means for preventing 15 the formation of an open space between the work support and anvil during such relative movement.

10. A machine for setting eyelets or the 15 like, having, in combination, setting devices, a 20 slideable plate having a slotted end constructed and arranged to serve as a work rest, an anvil plate having a flat guard plate extending into the slotted end of said slideable plate, and means for shifting the slotted 25 end of said plate without removing it from engagement with said guard plate.

11. A machine for setting eyelets or the 30 like, having, in combination, setting devices, a relatively movable work rest and anvil plate, and a guard plate mounted on one of said relatively movable members and freely slideable in a slot formed in the other of said members.

12. A machine for setting eyelets or the 35 like, having, in combination, setting devices, a work rest, an anvil plate movable with respect to said work rest and a guard plate mounted on said anvil plate and freely slideable in said work rest.

40 13. A machine for setting eyelets or the

like, having, in combination, setting devices, a work rest, a movable anvil plate, an upsetting die mounted therein and a guard plate having a reduced shank extending into said anvil plate, said shank serving to retain said 45 upsetting die in said anvil plate.

14. A machine for setting eyelets or the like, having, in combination, punching and 50 setting devices constructed and arranged to operate successively on the work, a work rest, a movable anvil plate, a cutting block mounted therein and a guard plate having a reduced shank extending into said anvil plate and serving to retain said cutting block in 55 said anvil plate.

15. A machine for setting eyelets or the like, having in combination, tools comprising a punch and a setting die arranged for movement in parallel paths, levers for moving said tools arranged for movement about a 60 common axis, one of said levers having an arm offset with respect to a corresponding arm of the other lever, and springs connected thereto and disposed in parallel relation.

16. A machine for setting eyelets or the 65 like, having, in combination, a movable head, tools arranged to reciprocate in said head, tool levers mounted on said head, a stop for each lever, and a spring connected with a pair of levers and acting to maintain each 70 lever of the pair normally in engagement with its stop.

In testimony whereof I have signed my name to this specification in the presence of two subscribing witnesses.

Copies of this patent may be obtained for five cents each, by addressing the "Commissioner of Patents, Washington, D. C."

It is hereby certified that in Letters Patent No. 1,122,310, granted December 29, 1914, upon the application of Fred A. Rumney, of Somerville, Massachusetts, for an improvement in "Eyeleting-Machines," errors appear in the printed specification requiring correction as follows: Page 1, line 85, for the words "edge gages" read *work engaging members*; same page, line 102, for the words "As herein" read *Preferably*; same page, line 106, for the word "Preferably" read *As herein shown*; page 2, strike out the paragraph comprised in lines 4-21; and that the said Letters Patent should be read with these corrections therein that the same may conform to the record of the case in the Patent Office.

Signed and sealed this 23rd day of February, A. D., 1915.

[SEAL.]

J. T. NEWTON,

Acting Commissioner of Patents.
